INVENTOR

Leo J. Wahl.
W.J. Wahl

Atty.

UNITED STATES PATENT OFFICE.

LEO J. WAHL, OF STERLING, ILLINOIS.

CLIPPERS.

Application filed February 4, 1924. Serial No. 690,442.

To all whom it may concern:

Be it known that I, LEO J. WAHL, a citizen of the United States, residing at Sterling, in the county of Whiteside and State of Illinois, have invented certain new and useful Improvements in Clippers, of which the following is a full, clear, and exact description, reference being had to the accompanying drawing, forming a part of this specification.

My invention relates to clippers primarily intended for use in barber shops, though it is capable of advantageous use in other places, and for purposes other than cutting hair.

One object of my invention is the provision of a structure to be operated by an alternating electric current.

Another object of my invention is to arrange the parts so that the member which usually serves as a pole piece, is mounted so that it moves, and by its movement, and through suitable connections moves the movable clipper blade, or the mechanism of the device.

Another object of my invention is to reduce the air gap between the stationary and movable pole pieces by locating all of the air gap at one point, thereby increasing the magnetic field and the available power.

Other objects of my invention will be described in the specification.

The novelty of my invention will be hereinafter more fully set forth, and specifically pointed out in the claims.

In the accompanying drawing:

Fig. 1 is a plan view of a clipper embodying my invention.

Fig. 2 is a side view of Fig. 1, the case being in section.

The same numerals of reference are used to indicate identical parts in both figures.

In constructing a clipper in accordance with my present invention, I provide a handle portion 1, to one end of which I attach the stationary clipper blade 2. The movable clipper blade 3 rests upon and is held in contact with the stationary clipper blade and cooperates therewith for the cutting operation.

A pair of electromagnetic coils 4, one of which is shown partly in section, are mounted in the handle portion and held in place by suitable clamps 5, these coils being fed by a suitable alternating current passing along the wires 6. One of the coils is pro-

vided with a stationary pole piece 7 which may be held in place by screws 8, that portion of the pole piece 7 which is farthest from the clipper blades being provided with a pivotal mounting 9 by means of which the movable pole piece 10 is mounted. The pole piece 10 as is clearly shown passes through the other coil 4 and this coil is provided with a sufficiently large opening to permit the movable pole piece to move through its range of travel.

The free end of the pole piece 10 carries a bracket 11 which serves as a mounting for a driving and tension screw 12, the latter being provided with a spring 13 which serves to hold it in any adjusting position, the lower end of the screw 12 entering a suitable opening in the movable blade 3 to not only drive this blade, but press it downwardly against the stationary blade 2.

To maintain the blade 3 in proper position, a guard 14, shown in Fig. 2 but removed from Fig. 1, is carried by the movable pole piece and its lower edge cooperates with a rib 15 formed on the upper face of the blade 3, the guard 14 serving as a closure for the front end of the handle portion so that the hair or material being cut does not enter the interior of the handle portion.

A cover 16 is provided for the handle portion to make the closure complete.

A spring 17 is mounted on the movable pole piece 10 adjacent its pivotal point 9, and an adjusting screw 18 passes through the handle portion and cooperates with the spring 17 to move the movable pole piece away from the stationary pole piece during the intervals between the periods of attraction between the stationary and movable pole pieces.

It is to be noted that the pivotal connection between the pole pieces 7 and 10 may be made of any length desired by increasing the vertical thickness of the ends of the pole pieces so that the upward thrust produced by the screw 12 may be properly resisted. It is also to be noted that by properly shaping the adjacent parts, the air gap at the pivotal end of the movable pole piece, and between it and the stationary pole piece may be reduced to practically nothing, without unduly increasing the friction of the moving parts which would be set up by actual contact between the rounded portions of the stationary and movable pole pieces at the pivotal point, from which it will be seen

that the magnetic field is complete with the exception of the one air gap near the clipper blades.

It is to be noted that by providing the 5 movable pole piece, and mounting it through one of the coils, this pole piece becomes magnetized simultaneously with the other pole piece but opposite and the movement produced by such a structure is consequently 10 more powerful than would be the case where a separate armature was used, because of the fact that the separate armature of the ordinary structure would not be magnetized but would be merely in the magnetic field.

15 Having thus fully described my invention, I claim:

1. In a clipper the combination of a handle portion, a pair of stationary electro-magnetic coils mounted therein, a stationary 20 pole-piece for one of said coils, a movable pole-piece extending into the other of said coils, and a moving element connected to said movable pole-piece to be moved thereby.

2. In a clipper the combination of a handle, a pair of stationary electro-magnetic coils mounted longitudinally therein, a stationary pole-piece for one of said coils, a movable pole-piece extending into the other of said coils, a moving element connected for operation to the movable pole-piece, and a spring for the movable pole-piece.

3. In a clipper the combination of a handle portion, a pair of electro-magnetic 35 coils mounted therein, a stationary pole-piece for one of said coils, a movable pole piece extending into the other coil, and adjustable spring mechanism for moving the movable pole piece away from the stationary pole piece.

4. In a clipper the combination of a handle portion, a pair of electromagnetic coils longitudinally mounted therein, a stationary pole piece for one of the coils, a 45 movable pole piece extending through the other coil and forming with the stationary

pole piece a substantially U shaped magnet, and a spring device for moving the movable pole piece away from the stationary pole piece.

5. In a clipper the combination of a handle portion, a pair of electromagnetic coils longitudinally mounted therein, a stationary pole piece for one of the coils, a movable pole piece extending through the 55 other coil and forming with the stationary pole piece a substantially U shaped magnet, a member connected for movement by and with the movable pole piece, and a spring for moving the movable piece away from the stationary piece.

6. A device of the character described comprising an electro-magnet comprising a pair of coils, a stationary core in one of said coils and a member mounted in the other of 65 said coils and movable toward and away from said core.

7. A device of the character described comprising an electro-magnet comprising a pair of coils, a stationary core in one of said 70 coils and a member mounted in the other of said coils and movable toward and away from said core at one end thereof.

8. A device of the character described comprising a casing, an electro-magnet comprising a pair of coils lying lengthwise in said casing, a stationary core in one of said coils and a member extending through the other of said coils and movable toward and away from said core.

9. A device of the character described comprising an electro-magnet comprising a pair of coils, a stationary core in one of said coils and an armature mounted in the other of said coils and movable toward and away 85 from said core.

10. A device of the character described comprising an electro-magnet comprising a pair of coils, a stationary core in one of said coils and a core extending through the other 90 of said coils and movable transversely thereof.

LEO J. WAHL.
